Primary Examiner — Ryan Harvey(74) *Attorney, Agent, or Firm* — Zhihua Han; Wen IP LLC(57) **CLAIM**

I claim the ornamental design for a trampoline, as shown and described.

DESCRIPTION

FIG. 1 is a perspective view of a trampoline, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of portion 8 of FIG. 3.

1 Claim, 8 Drawing Sheets(56)
